UNITED STATES PATENT OFFICE

2,549,986

MEANS FOR TRANSMITTING MECHANICAL MOTION THROUGH A FLUIDTIGHT WALL

John R. Oliver, Springfield, Mass., assignor to United Shoe Machinery Corporation, Flemington, N. J., a corporation of New Jersey

Original application January 20, 1945, Serial No. 573,799. Divided and this application December 8, 1947, Serial No. 790,362

3 Claims. (Cl. 74—519)

1

This invention relates to means for transmitting mechanical motion through a fluid-tight wall and is herein illustrated as embodied in apparatus including a pelorus or sighting instrument mounted on the deck of a submarine. The illustrated apparatus includes direction indicating means mounted in a fluid-tight housing. In the illustrated apparatus the means for transmitting mechanical motion is part of a signaling system whereby the observer signals the control room of the submarine when the pelorus or sighting instrument is accurately trained on a target. The signaling system includes a micro-switch which is mounted in the housing to protect it from the elements.

It is an object of the present invention to provide means conveniently arranged with relation to the pelorus whereby the observer may readily operate the micro-switch to transmit a signal to the control room. With this in view the invention contemplates the provision of motion transmitting means comprising a lever extending through an opening in the wall of the housing and means sealing said opening against water under pressure comprising a plug having a frusto-conical bore through which the motion transmitting lever extends, and a flexible element bonded to the frusto-conical surface of said plug and also to said lever. It is important that provision be made for preventing accidental operation of said motion transmitting lever by the action of the sea against the outwardly projecting portion of said lever when the submarine is submerged. To this end the invention provides, in combination with the motion transmitting lever and the flexible element above referred to, means actuated by external pressure against said lever for rendering it inoperative. As herein illustrated, said means comprises an abutment extending inwardly from the frusto-conical surface of the plug and arranged to cooperate with means extending outwardly from the motion transmitting lever.

After the observer transmits a signal to the control room through the signaling system above described, the officer in the control room determines the bearing of the target by reading indicating mechanism which is operated by the electrical transmitting devices of a "selsyn system," so called, embodied in the deck assembly, and illustrated and described in an application for United States Letters Patent, Serial No. 573,799, filed January 20, 1945, in my name, of which the present application is a division.

The invention will now be described with refer-

2

ence to the accompanying drawings and pointed out in the appended claims.

In the drawings,

Fig. 1 is a front elevation illustrating apparatus embodying the features of the present invention, the base portion of the apparatus being broken away

Fig. 2 is a section on the line II—II of Fig. 1; and

Fig. 3 is a detail view in elevation illustrating mechanism for operating a micro-switch.

In Fig. 1 there is illustrated a pelorus mounted on the deck of a submarine. The illustrated pelorus comprises a pair of binoculars 12 suspended on a hanger 12 having right and left handles 14 and 16 whereby the observer swings the binoculars in azimuth and in elevation. The hanger is mounted for swinging movement in elevation on headed pins 18 at the upper extremities of standards 20 secured to a bezel ring 22. The bezel ring is secured to a circular housing 24 having a downwardly extending hub (not shown) mounted in suitable bearings in a housing 26 to permit movement of the binocular mount in azimuth. The assembly above described is supported in a circular frame 28 secured to a rigid portion of the superstructure of the submarine and so arranged thereon that the binoculars are positioned approximately at the eye level of the observer. The frame 28 is in the form of a flanged ring arranged horizontally on the superstructure of the submarine and having upward extensions or standards 30 at opposite sides thereof which provide bearings for a gimbal mechanism in which the illustrated assembly is suspended. The gimbal mechanism comprises a ring 32 having outwardly projecting trunnion pins 34 journaled in bearings in the upper portions of the standards 30. The ring 32 provides a mounting for the housing 26, said housing having outwardly and upwardly extending arms 36 pivotally mounted on bolts 38 projecting outwardly from the ring 32 at points angularly spaced 90° from the bearings of the ring in the standards. The housing 24 provides a water-tight closure having mounted therein indicating mechanism whereby the observer may determine the setting of the binoculars in azimuth and the housing 26 provides a water-tight closure for synchronous generators which are actuated by movement of the binoculars in azimuth. The synchronous generators are electrically connected to synchronous motors located in the control room of the submarine and arranged to operate mechanism which indicates the angular position of the binoculars in azimuth

relatively to the longitudinal center line or rubber line of the submarine.

In order to enable the observer to signal the control room when the line of sight of the binoculars has been brought to bear on the target, means is provided in the right handle 14 of the hanger 12 for operating a micro-switch 40 (Fig. 3) mounted in the housing 24. The illustrated mechanism for operating the micro-switch comprises a plunger 42 (Fig. 2) mounted for vertical movement in the handle 14 and yieldingly held at the limit of its upward movements by a spring 44 surrounding the plunger and confined between the head 46 of the plunger and the base of a counterbore in the handle. Downward movement of the plunger 42 by pressure of the thumb of the observer on the head of the plunger rocks a lever 48 pivoted on the standard 20 in a clockwise direction as seen in Fig. 1. In order that the plunger may operate the lever 48 in any position of the hanger 12, within its normal range of rotary movement on the pins 18, the plunger has secured to its reduced lower end portion an arcuate shoe 50 arranged to engage the outer end portion of the lever 48, said shoe being so arranged that the center of its arc coincides with the axis of rotation of the hanger when the plunger is in its position illustrated in Fig. 1. For securing the arcuate shoe 50 to the plunger said shoe has an outwardly extending lug 52 which is bored to receive the reduced lower end portion of the plunger, said lug being clamped to a shoulder in the plunger by a nut 54. The lever 48 is connected to a switch operating lever 56 (Fig. 3) by a link 58 pivotally connected to the inner end portion of the lever 48 and bored at its lower end portion to receive the outwardly projecting portion of the lever 56. The upward movement of the link 58 by the operation of the plunger 42 is imparted to the lever 56, the bore in the link being large enough to permit the required operating movement of the lever. The lever 56 is secured in a mounting constructed and arranged to permit rocking movement of the lever sufficient to operate the micro-switch 40 while excluding water under pressure from the closure in the base of the pelorus. As illustrated in Fig. 3 the lever 56 is mounted in a central opening in a resilient rubber ring 60 and is securely bonded thereto to prevent seepage of water along the joint between the lever and the ring. The frusto-conical peripheral surface of the ring 60 is bonded to the complementally shaped inner wall of a hollow screw plug 62 which is threaded into a suitable opening in the cylindrical base member 64 of the pelorus. The inner end face of the ring bears against an annular abutment plate 66 fixed in the hollow plug 62, said plate serving to take the force of the sea water pressure against the ring when the submarine is submerged. In order to increase the flexibility of the ring 60 it is cut away as indicated at 68 in Fig. 3 in order to reduce to a minimum thickness the inner body portion of the ring while providing a maximum bonding surface of the ring on the lever 56 and the plug 62.

In order to prevent accidental operation of the micro-switch by the action of the sea on the exposed mechanism for operating the lever 56 said lever is provided with a peripheral flange 70 and the rubber ring 60 is cut away in the region of said flange so that when the pressure of the sea acts on the exposed end face of the lever and the ring there will be a metal-to-metal contact of the flange with the abutment plate. When

the submarine is submerged the pressure of the sea water against the end face of the lever 56 causes the flange 70 embedded in said ring to act against the abutment plate to retain the lever in its horizontal position with the inner end of said lever out of contact with the micro-switch. When the submarine is on the surface the flange 70 is sufficiently separated from the abutment plate 66 by the intervening flange of the ring 60 to permit free movement of the lever 56 within the range required for operation of the micro-switch.

It will be understood that the utility of the illustrated mechanism for transmitting mechanical motion through a fluid-tight wall is not limited to its illustrated embodiment in a pelorus on the deck of a submarine, nor is it limited to mechanism for operating a micro-switch.

Having thus described my invention, what I claim as new and desire to secure by Letters Patent of the United States is:

1. Means for transmitting mechanical motion through a fluid-tight wall comprising a motion transmitting member extending through an opening in said wall, means sealing said opening against fluid under pressure including a flexible plug surrounding said member and constructed and arranged to accommodate motion transmitting movement thereof, an abutment for said plug fixed relatively to said wall, and a projection on said motion transmitting member so constructed and arranged that external pressure against said member causes the projection and the abutment to cooperate to hold said member against motion transmitting movement.

2. Means for transmitting mechanical motion comprising an arm extending through an opening in a wall, a closure for said opening comprising a plug having a bore enclosed by a frusto-conical surface, a flexible element bonded to the frusto-conical surface of said plug and surrounding and bonded to said arm, and a rigid abutment extending inwardly from the frusto-conical surface of the plug and arranged to sustain pressure against said flexible element.

3. Means for transmitting mechanical motion through a fluid-tight wall comprising a motion transmitting member extending through an opening in said wall, means sealing said opening against fluid under pressure including a flexible element surrounding said member and constructed and arranged to accommodate motion transmitting movement thereof, a fixed abutment member and a projection on said motion transmitting member constructed and arranged to be brought into engagement with said abutment member by external pressure against said motion transmitting member.

JOHN R. OLIVER.
